JALOUSIE OPERATOR

Donald H. McGogy, Menlo Park, Calif., assignor
to Dalmo Victor Company, San Carlos, Calif.,
a corporation of California

Application January 11, 1952, Serial No. 265,985

12 Claims. (Cl. 192—8)

1

This invention relates to a mechanical operator and particularly to a jalousie operator.

A main object of the present invention is to provide a mechanical operator which can be used to adjust a wide range of devices such as valves, dampers, pushing devices for turn tables or platforms, etc., and in fact any device where load reactions on the controlled device might disturb the adjustment and wherever the use of a single force to both unlock and actuate the operator would be necessary or convenient. Although the invention will be described in connection with a jalousie operator, the invention is not intended to be limited by this description unless specifically set out in the claims.

A principal object of the present invention is to provide an improved jalousie operator, and particularly to provide a self-locking jalousie operator, operable to automatically unlock to permit operation thereof and therefore adjustment of the slats of a jalousie, and to automatically resume a locking condition after adjustment of the slats to thereby retain the slats in adjusted position.

Another object of the present invention is to provide a self-locking jalousie operator as above described which is simple and inexpensive in construction, reliable in operation, compact, and readily applied to a window frame.

Various other objects of the present invention will be apparent from the following description taken in connection with the accompanying drawings in which:

Fig. 1 is a fragmentary cross-sectional view in side elevation through a window of the jalousie type having a jalousie operator of the present invention incorporated therein.

Fig. 2 is a fragmentary cross-sectional view in side elevation taken through the jalousie operator disclosed in Fig. 1 and showing the parts of the jalousie operator in the positions they occupy when the operator is locked and when the slats are in closed position.

Fig. 3 is a horizontal cross-sectional view taken along line 3—3 of Fig. 2 in the direction of the arrows.

Fig. 4 is a vertical cross section taken along line 4—4 of Fig. 2 in the direction of the arrows.

Figs. 5 and 6 show diagrammatically the positions occupied by certain of the parts in the jalousie operator when the operator is being operated for movement in opposite directions.

Referring to the accompanying drawings, wherein similar reference characters designate similar parts throughout, Fig. 1 shows a jalousie

operator generally indicated as 9 being mounted on a jamb 10 of a window frame generally entitled 11 and connected by a link 13 to a travel bar 15. Travel bar 15 is connected by levers 17 to a plurality of slats 19 which are adapted to be adjusted in various angular positions through operation of the jalousie operator 9. Slats 19 are pivotally connected at 21 to the jambs of window frame 11, the general construction of such a jalousie window not being a particular part of the present invention and therefore only described generally.

Jalousie operator 9 includes a case 22 containing a part of the operating mechanism of the jalousie operator. Case 22 assumes the form of an open box casting recessed in jamb 10 and held in place by a mounting plate 23, secured to the case by screws 23a and to the jamb by screws 23b. There is an escutcheon plate 24 secured to the righthand wall of case 22 by screws 24a and to the jamb 10 by screws 24b. The operating mechanism of the jalousie operator 9 includes a first class composite lever 25 which is pivotal about a pivot pin 27, and at its inner or lefthand end, as the parts are depicted in Fig. 2, is operatively connected to a lever-actuated vertically movable traveling yoke 29 by a pivot pin 31 and a roller 32 carried thereon and disposed within the groove of a horizontally grooved guide block 33 which is secured to traveling yoke 29 by rivets 34. Guide block 33 permits lateral movement of the arcuately movable pivot pin 31 and roller 32 relative to the linearly movable traveling yoke 29 upon operation of lever 25. Traveling yoke 29 is connected by a pivot pin 35 to previously mentioned link 13 whereby slats 19 can be opened, closed or adjusted to any intermediate position by operation of lever 25.

Mounting plate 23 has an oblong slot 36 therein through which pivot pin 35 extends and within which pivot pin 35 travels. Jamb 10 is suitably recessed to accommodate the movement of yoke 29. Escutcheon plate 24 and the wall of case 22 to which it is attached have registered oblong openings formed therein to accommodate the movement of lever 25.

To hold slats 19 in any desired position of adjustment, a releasable locking mechanism is provided. This locking mechanism includes a locking rod 37 secured at its ends by screws 38 to end flanges 38a on yoke 29 and slidably receivable through the upper and lower walls of a case 22 and through a pair of latching plates 40. Latching plates 40 are pivotally mounted at their left-hand ends, as the parts are depicted in Fig. 2, in

3

notches 40a formed on case 22, and urged apart by a compression spring 41 secured to the plates by rivets 41a.

Latching plates 40 have the apertures thereof, receiving locking rod 37, of a size to loosely receive the locking rod so that the latching plates, under the influence of compression spring 41, assume positions angularly transecting the locking rod. Since such latching plates are, per se, old in the art apart from the present combination, it is apparent to those skilled in the art that the upper latching plate will prevent upward movement of locking rod 37 and the lower latching plate will prevent downward movement of locking rod 37.

For automatically effecting a release of latching plates 40, a release member 43 is provided and pivotally mounted at its lefthand end to case 22 by a pivot pin 47 and operatively connected by the previously mentioned pivot pin 27 to composite lever 25. It is apparent that pivot pin 31 will be held stationary and therefore lever 25 will be held relatively stationary, by the engagement of latching plates 40 with locking rod 37 until a release of the appropriate plate is effected, and, therefore, during the first increment of movement of lever 25 in either of its directions of movement, lever 25 functions as a second class lever, pivoting about pivot pin 31 and swinging release member 43 through the medium of pivot pin 27 in the same direction of movement as the handle end of lever 25.

However, only limited movement of release member 43 is permitted, said release member at its righthand end engaging a stop 49 when lever 25 is pivoted clockwise, and engaging a stop 50 when lever 25 is pivoted counterclockwise, said stops being formed on case 22 (see Figs. 5 and 6). After engagement with either stop 49 or 50, release member is stationarily held and lever 25 thereafter operates as a first class lever to urge traveling yoke 29 in the opposite direction from which force is applied to the handle end of the lever. In order to release the yoke for movement, release member 43 has a pair of latch-engaging screws 51 threadedly received by offset ears 52 formed on release member 43. One of the screws 51 is adapted, when the release member is moved in one direction, to engage the adjacent latching plate, and the other of which is adapted to engage the other latching plate when the release member is moved in the opposite direction. (Compare Figs. 5 and 6). Such engagement moves the latching plates, individually and separately, from their normal latching positions to positions where their bores are more nearly aligned with locking rod 37, and holds the latching plates, individually and separately, against pivotal movement in the direction urged by locking rod 37, thereby permitting the locking rod to slide through the latching plates and therefore permitting adjustment of slats 19 by operation of lever 25. Release member 43 is moved to a non-releasing position, after lever 25 is released, by a leaf spring 55 secured at one end to case 22 and at its opposite end to release member 43. Release member 43, during such movement, carries lever 25 therewith, the operative connection of pivot pin 31 and roller 32 in guide block 33 permitting such movement of lever 25.

Screws 51, by virtue of their threaded engagement with ears 52, are adjustable toward and away from their respective latching plates, and adjusted so that when release member 43 is in

its non-releasing position, the inner opposed ends of the screws are disposed closely adjacent to but spaced from their respective latching plates. Screws 51 are held in their adjusted positions by compression springs 57. Screws 51 have hex heads to facilitate easy adjustment of the screws.

Composite lever 25 includes a tapered socket portion 61 and a removably tapered handle portion 63 fitting in the socket portion. The handle portion is preferably removed after adjustment to avoid possible injury to a person passing the window.

Although the operator is shown as being directly manually operated, it is apparent that the device could be remotely controlled such as by rope, chain or push rod arrangement.

By the present invention, a jalousie operator has been provided which is self-locking so that while it may be readily operated to adjust the slats of a jalousie window construction to any desired position, the jalousie operator is operable to prevent movement of the slats initiated by a force imposed directly on the slats or in any other manner except by a force imposed on the lever.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A jalousie operator, comprising a case, a locking member slidably extending through said case and having means for attachment to a jalousie type window construction for operating the same, latching means for preventing movement of the locking member, having two releasing positions in either of which said locking member is released for movement, a release member pivotally mounted on the case and engageable with said latching means and adapted to be pivoted in one direction to move said latching means to one of its releasing positions and in the opposite direction to move said latching means to the other of its releasing positions, a lever pivotally connected to both the locking and release members for operating the same, operable upon pivotal movement in one direction to pivot said release member one way to release the locking member for movement in one direction, and operable upon pivotal movement in the opposite direction to pivot said release member the opposite way to release the locking member for movement in the opposite direction.

2. A jalousie operator, comprising a case, a locking member slidably extending through said case and having means for attachment to a jalousie type window construction for operating the same, latching means for preventing movement of the locking member, having two releasing positions in either of which said locking member is released for movement, a release member pivotally mounted on the case and engageable with said latching means and adapted to be pivoted in one direction to move said latching means to one of its releasing positions and in the opposite direction to move said latching means to the other of its releasing positions, means for limiting pivotal movement of the release member in either direction, and a lever pivotally connected to both the locking and the release members for operating the same, operable upon pivotal movement in one direction to pivot said release member to one of its limits to effect a release of the

locking member for movement in one direction, and operable upon pivotal movement in the opposite direction to pivot said release member to the other of its limits to effect a release of the locking member for movement in the opposite direction.

3. A jalousie operator, comprising a case, a locking member slidably extending through said case and having means for attachment to a jalousie for operating the same, a pair of latching plates pivoted at one set of ends on the case, spring-urged in opposite directions, and so apertured to accommodate the locking member that said plates angularly transect the locking member, whereby one latching plate is operable to prevent movement of the locking member in one direction, and the other latching plate is operable to prevent movement of the locking member in the opposite direction, a release member pivotally mounted on the case and operable when pivoted in one direction to engage one of the latching plates to pivot the same to unlatching position to release said locking member for movement in one direction, and operable when pivoted in the opposite direction to engage the other of the latching plates to pivot the same to unlatching position to release said locking member for movement in the opposite direction, and a lever pivotally connected to both the locking and release members for operating the same, operable upon pivotal movement in one direction to pivot said release member one way to release the locking member for movement in one direction, and operable upon pivotal movement in the opposite direction to pivot said release member the opposite way to release the locking member for movement in the opposite direction.

4. A jalousie operator, comprising a case, a locking member slidably extending through said case and having means for attachment to a jalousie for operating the same, a pair of latching plates pivoted on the case at one set of ends, spring-urged in opposite directions, and so apertured to accommodate the locking member that said plates angularly transect the locking member, whereby one latching plate is operable to prevent movement of the locking member in one direction and the other latching plate is operable to prevent movement of the locking member in the opposite direction, a release member pivotally mounted on the case and operable when pivoted in one direction to engage one of the latching plates to pivot the same to unlatching position to release said locking member for movement in one direction and operable when pivoted in the opposite direction to engage the other of the latching plates to pivot the same to unlatching position to release said locking member for movement in the opposite direction, means for limiting pivotal movement of the release member in either direction, and a lever pivotally connected to both the locking and release members for operating the same, operable upon pivotal movement in one direction to pivot said release member to one of its limits to effect a release of the locking member for movement in one direction and operable upon pivotal movement in the opposite direction to pivot said release member to the other of its limits to effect a release of the locking member for movement in the opposite direction.

5. A jalousie operator, comprising a case, a locking member slidably extending through said case and having means for attachment to a jalousie type window construction for operating the

same, latching means for preventing movement of the locking member, having two releasing positions in either of which said locking member is released for movement, a release member pivotally mounted on the case and engageable with said latching means and adapted to be pivoted in one direction to move said latching means to one of its releasing positions and in the opposite direction to move said latching means to the other of its releasing positions, means for limiting pivotal movement of the release member in either direction, means for urging said release member to remain in non-releasing position, and a lever pivotally connected to both the locking and release members for operating the same, operable upon pivotal movement in one direction to pivot said release member to one of its limits to effect a release of the locking member for movement in one direction, and operable upon pivotal movement in the opposite direction to pivot said release member to the other of its limits to effect a release of the operating member for movement in the opposite direction.

6. A jalousie operator, comprising a case, a locking member slidably extending through said case and having means for attachment to a jalousie for operating the same, a yoke secured to the ends of the locking member, latching means for preventing movement of the locking member having two releasing positions, in either of which said locking member is released for movement, a release member pivotally mounted on the case and engageable with said latching means and adapted to be pivoted in one direction to move said latching means to one of its releasing positions and in the opposite direction to move said latching means to the other of its releasing positions, and a lever pivotally connected to the yoke intermediate the ends thereof and to the release member for operating the same, operable upon pivotal movement in one direction to pivot said release member one way to release the locking member for movement in one direction, and operable upon pivotal movement in the opposite direction to pivot said release member the opposite way to release the locking member for movement in the opposite direction.

7. A jalousie operator, comprising a case and having means for attachment to a jalousie for operating the same, a yoke secured to the ends of the locking member, a transverse roller guide on the yoke, latching means for preventing movement of the locking member, having two releasing positions, in either of which said locking member is released for movement in one of two directions, a releasing member pivotally mounted on the case and engageable with said latching means and adapted to be pivoted in one direction to move said latching means to one of its releasing positions, and in the opposite direction to move said latching means to the other of its releasing positions, and a lever pivotally connected to the release member and having a roller receivable within the roller guide of the yoke, operable upon pivotal movement in one direction to pivot said release member one way to release the locking member for movement in one direction, and operable upon pivotal movement in the opposite direction to pivot said release member the opposite way to release the locking member for movement in the opposite direction.

8. A jalousie operator, comprising a case, a locking member slidably extending through said case and having means for attachment to a

jalousie for operating the same, a yoke secured to the ends of the locking member, a transverse roller guide on the yoke, a pair of latching plates pivoted to the case at one set of their ends, spring-urged in opposite directions, and so apertured to accommodate the locking member that said plates angularly transect the locking member, whereby one latching plate is operable to prevent movement of the locking member in one direction and the other latching plate is operable to prevent movement of the latching member in the opposite direction, a release member pivotally mounted on the case and operable when pivoted in one direction to engage one of the latching plates to pivot the same to unlatching position to release said locking member for movement in one direction, and operable when pivoted in the opposite direction to engage the other of the plates to pivot the same to its unlatching position to release said locking member for movement in the opposite direction, means for limiting pivotal movement of the release member in either direction, and a lever pivotally connected to both the locking and release members operable upon pivotal movement in one direction to pivot said release member to one of its limits to effect a release of the locking member for movement in one direction, and operable upon pivotal movement in the opposite direction to pivot said release member to the other of its limits to effect a release of the locking member for movement in the opposite direction.

9. An operator as set out in claim 1 in which there are means for urging the lever to remain in an inoperative position.

10. A self-locking operator, comprising a frame, a locking member carried by the frame for movement in either of two opposite directions and adapted to be connected to the device to be operated, a pair of pivoted latching members through which the locking member extends, said latching members being spring urged in opposite directions so that one latching member tends to prevent movement of said locking member in one direction and the other latching member tends to prevent movement of said locking member in the opposite direction, a releasing element movable in one direction to engage one latching member to release said locking member from the influence of said one latching member, a second releasing element movable in one direction to engage the other latching member to release said locking member from the influence of said other latching member, and a movable operating arm operatively associated with the releasing elements and being connected to the frame and locking member by means including a lost-motion connection to adapt the operating arm for selective actuation of the releasing elements prior to the time the operating arm positively actuates the locking member.

11. A self-locking operator, comprising a frame, a locking member carried by the frame for movement in either of two opposite directions and adapted to be connected to the device to be operated, a pair of latching members mounted on the frame for pivotal movement about stationary

axes, said locking member extending through said latching members, said latching members being spring urged in opposite directions so that one latching member tends to prevent movement of said locking member in one direction, and the other latching member tends to prevent movement of said locking member in the opposite direction, a releasing element movable in one direction to engage said one latching member to release the locking member from the influence of said one latching member, a second releasing element movable in one direction to engage said other latching member to release said locking member from the influence of said other latching member, and an operating arm operatively associated with the releasing elements and being pivotally connected to the frame and locking member by means including a lost-motion connection to adapt the operating arm for selective actuation of the releasing elements prior to the time the operating arm positively actuates the locking member.

12. A self-locking operator, comprising a frame, a locking member mounted in the frame for movement in either of two opposite directions and adapted to be connected to the device to be operated, a pair of latching members mounted on the frame for pivotal movement about stationary axes, said locking member extending through said latching members, said latching members being spring urged in opposite directions so that one latching member tends to prevent movement of said locking member in one direction, and the other latching member tends to prevent movement of said locking member in the opposite direction, a releasing member movable on the frame for movement in one direction to actuate said one latching member and release the locking member for movement in one direction, and movable in the opposite direction to actuate the other latching member to release the locking member for movement in the opposite direction, a movable operating arm operatively associated with the releasing member and being connected to the frame and the locking member by means including a lost-motion connection to adapt the operating arm for actuation of the releasing member prior to the time the operating member positively actuates the locking member, and spring means urging the releasing member into a neutral position.
